CAN VENDING MACHINE

Joseph B. Donnelly, Wyoming, Ohio, assignor to Schenley Industries, Inc., New York, N. Y., a corporation of Delaware

Original application November 24, 1950, Serial No. 197,298. Divided and this application August 30, 1954, Serial No. 452,904

4 Claims. (Cl. 193—27)

This invention relates to new and useful improvements in can vending machines. This application is a division of my application Serial No. 197,298 filed November 24, 1950 for Can Vending Machine.

More particularly, the invention relates to a novel chute construction and a novel dispensing mechanism for vending machines for cans.

The chutes described herein are formed by apposed vertical walls formed of a plurality of superposed plate sections. The opposed walls are held a fixed distance apart by sleeve spacers through which pass bolts engaging said plate sections. The sections are joined by lugs projecting upward from their upper edges overlapping the section above, certain of said bolts passing through holes in the lugs and through holes in the plate sections in the area overlapped by said lugs. Thus the chutes may be made in heights which are multiples of the heights of plate sections. The relatively small sections may be manufactured more easily and inexpensively than complete walls. The walls may be assembled rapidly and conveniently and, upon tightening of the bolts, said walls are rapidly locked together.

The dispensing mechanism employed herein is coin-actuated to dispense cans as they roll down the chute one at a time. A pair of slideable pins is mounted so that each pin in its protracted position obstructs the passage of cans down the chute and in its retracted position the pin does not obstruct passage. The pins are so actuated that when one is protracted, the other is retracted. Upon deposit of a coin, the lowermost pin retracts, permitting dispensing of the lowermost can, and the other pin projects, preventing other cans from following the first can. Thereafter, the positions of the pins are reversed and the next can moves into position abutting the first pin.

Another feature of the invention is the association of two or more chutes with a single coin slot. When one chute is empty, the cans in the next chute are dispensed until all of the chutes are empty, whereupon additional coins deposited by a customer are returned and a light may be energized to indicate that the chutes are empty.

Other objects of the present invention will become apparent upon reading the following specification and referring to the accompanying drawings in which similar characters of reference represent corresponding parts in each of the several views.

In the drawings:

Fig. 1 is a vertical mid-section of the machine.

Fig. 2 is a vertical section taken substantially along the line 2—2 of Fig. 1. The line 1—1 on the figure indicates the location of the section of Fig. 1.

Fig. 3 is an enlarged vertical section of the dispensing mechanism and associated parts, showing said mechanism immediately after vending of the can.

Fig. 4 is an enlarged portion of the dispensing mechanism showing the parts immediately after their position as shown in Fig. 3.

Fig. 5 is a wiring diagram of the machine.

2

Fig. 6 is a vertical section taken substantially along the line 6—6 of Fig. 1, the same being partially broken away.

The machine illustrated in the accompanying diagrams is particularly designed for vending, upon the deposit of a suitable coin, cans 20 of beverages such as beer and ale, which preferably are kept at a low temperature by refrigerating means incorporated in the machine. It will be understood that the mechanism hereinafter described may be used for vending other commodities.

A suitable insulated cabinet 21 is provided, said cabinet having refrigerating coils 22 adjacent the top thereof which are connected to a suitable compressor 23 located outside the insulated area of the cabinet as is well understood in refrigerating art. The presence of the refrigerating coils 22 within the cabinet causes the circulating therethrough of chilled air which, by thermostatic controls (not shown), maintains the interior of the cabinet 21 at a suitable temperature depending upon the type of comestible stored therein.

The vending machine illustrated particularly in Figs. 1 and 2 contemplates the use of two coin deposit slots 24, each of said slots being associated with a pair of can chutes 26. Thus a customer may deposit a coin in either of the two coin slots 24 provided, whereupon a can 20 will be dispensed from one or the other of the two chutes of the pair associated with said slot. After the supply of cans in one chute of the pair of chutes is exhausted, the cans in the other of the pair of chutes will be dispensed. After all of the cans in both pairs of chutes are dispensed, a light 27 will be illuminated to indicate that the cans are exhausted and any coin thereafter inserted in the slot 24 will be returned to the customer.

The chutes are constructed by the suitable location within the cabinet of parallel vertical walls 28 extending from adjacent the front of the cabinet to adjacent the rear of the cabinet and resting on the floor of the insulated portion thereof. Said walls are spaced apart a distance slightly greater than the height of the cans 20 to be dispensed by the machine, it being understood that said cans are inserted with their axes disposed horizontally. Each wall 28 is made up of a plurality of sections 29 suitably joined together along horizontal joints as hereinafter appears. Each said section 29 comprises a relatively thin, light-weight plate having on each side a trackway 31 extending from the front top corner (reference numeral 32) rearwardly and downwardly at an angle of approximately 7° with the horizontal to the rear middle of the section (reference numeral 33). The trackway then bends around through an angle of approximately 166° and extends forwardly and downwardly at an angle of approximately 7° to the front lower corner (reference numeral 34) of the section where it joins the upper forward portion 32 of the trackway of the next lower section. The trackways are formed by narrow raised beads 36 and 37 formed integrally with the plate and projecting outward from each surface thereof, one said bead 36 providing a vertical support for the cans as they roll rearwardly of the chute and thereupon being disposed immediately above the cans as they roll forwardly. The other said bead 37 is disposed along the top of the path of the cans as they roll rearwardly and then provides a vertical support as the cans roll forwardly. The beads 36 and 37 are curved about a radius slightly greater than the can diameter along the outside of the curves in the can path as indicated by reference numerals 38 and 39 and come to points 41 and 42 at the inside of the curves in the can path, the points 41 and 42 being the centers of the radii of curvature of the curved portions 38 and 39, respectively. Beads 36 and 37 are spaced apart a distance slightly greater than the diameter of the cans 20 being dispensed. The portions of the beads 36 and 37 disposed along the bottom of the pathway provide a support for the end seam beads of the cans as they roll down the chute section and the portions

60 65 70 75 80 85 90 95

disposed above the top of the pathways prevent the cans from raising out of position and possibly jamming in the machine. The two beads cooperate to confine the cans within the desired undulate pathway. Since the wall sections 29 are spaced apart a distance only slightly greater than the length of the cans 20, there is no possibility of the cans being slanted sideways if they are once properly placed within the chutes. Sections 29 are apertured as indicated by reference numeral 43 to provide for circulation of cold air in the portions thereof which are not a part of the chute structure proper.

The individual sections 29 are joined together by means of ears 46 integrally formed with these sections along the top edges thereof and projecting above the top edges thereof and overlapping and overlying the next section above, said ears being laterally offset so as to overlap the section above, as shown particularly in Fig. 6. Bolts 47 hereinafter described pass through projecting ears 46 and holes adjacent the lower edge of the section overlapped thereby to hold the superimposed sections together. The bolts are used also to hold the walls in proper alignment. Suitable sleeves 48 extending between opposite walls of each section 29 surround said bolts 47 and are of such length that they space the opposed sections 29 apart the required distance and, since their ends are square, hold said sections in proper alignment. A plurality of additional bolts 49 and sleeves 48 is located in suitable and accessible places in walls of the chute so as to assist in securing proper alignment and spacing of said walls.

As seen particularly with reference to Fig. 1, a suitable door 56 is provided in the top of the cabinet 21 through which cans 20 may be inserted. The attendant inserts said cans 20 so that they lie with their axes horizontal and their end seam beads resting on beads 36 and 37. As each can is dispensed the remaining cans in the chute roll 35 down until all of the cans in the chute are exhausted. 30

40 down until all of the cans in the chute are exhausted. 41
42 Adjacent the bottom of each chute of a pair of chutes
43 is an empty switch 57 and 58, said switch being a micro-
44 switch or similar switch mechanism. The weight of the
45 cans in the chute resting on resilient fingers 59 maintains
46 said switches 57 and 58 closed so long as there is a can
47 in the chute. When all the cans have been dispensed, the
48 resilient finger 59 rises and the electrical contact is
49 broken. A second switch 61 is maintained at the bottom
50 of one of said chutes, herein called the second chute, said
51 switch 61 being biased closed, but maintained closed by
52 the weight of the cans in the chute on resilient finger 62.
53 When all of the cans have been exhausted, resilient finger
54 62 opens switch 61 and this causes empty light 27 lo-
55 cated exteriorly of cabinet 21 to be illuminated, notifying
56 the attendant to refill the chutes and also indicating to a
57 potential customer that all of the cans in the chutes asso-
58 ciated with a particular coin slot 24 have been dispensed
59 so that said customer will not deposit a coin in the slot.

The dispensing mechanism is shown particularly in Figs. 3 and 4. Said mechanism is located adjacent the bottom of each chute. It comprises essentially a pair of vertically slideable pins 66 and 67, each of said pins having an up and a down position and when in up position extending into trackway 31 a distance sufficient to prevent a can from rolling past said pin. Said pins 66 and 67 are slideable in vertical bushings 68 extending upward through the bottom wall of the cabinet 21. Preferably the upper ends of said pins 66 and 67 are pointed and conical suitably to engage the round body of the can lowermost in the chute.

The lower ends of said pins are pivotally connected to the opposite arms of a T-shaped link 71, said T-shaped link being disposed with its upper portion 72 substantially horizontal, one end of said upper portion 72 being connected to pin 66 by means of a slot-and-pin connection and the other end of said upper portion 72 being connected to pin 67 by a similar slot-and-pin connection. The T-shaped member 71 is pivotally mounted to a stationary portion of the cabinet by means of a pivot 73 passing

through approximately the center of the horizontal portion 72 of link 71. The lower end of T-shaped member 71 is connected by a slot-and-pin connection to the horizontally slideable solenoid arm 76. Spring 77 normally biases said T-shaped member 71 to the position shown in Fig. 4 so that the pin 66 engages the lowermost can in the chute. However, upon a customer depositing a suitable coin in slot 24, an electrical circuit is established which energizes solenoid 78 and retracts arm 76 which moves the T-shaped member to the position shown in Fig. 3 whereupon pin 66 is retracted allowing the lowermost can to escape and pin 67 is simultaneously projected restraining the next can in order from following the first can out of the machine. The retraction of the solenoid 78 is for only a brief period of time, sufficient for passage of the coin through coin switch mechanism 79, whereupon spring 77 restores T-shaped member 71 to the position shown in Fig. 4, thereby retracting pin 67 allowing the cans to move downward one position, the last can in order resting against pin 66 until a customer inserts another coin in the machine. An insulated trap door 81 is provided in the cabinet adjacent the lower end of chute, said trap door being mounted on pivoted arms 82 suitably counter-weighted by weight 83 so that it is normally in horizontal position closing off the bottom of the insulated portion of the cabinet, thereby preventing the waste of cooling medium. The weight of a can being dispensed resting upon trap door 81 is sufficient to overcome the counter-weight 83 and hence the trap door swings down into the position shown in Fig. 3, whereupon the can rolls into the dispensing station 84 where the customer may manually remove the can. It will be understood that a suitable can opener (not shown) may be installed in the cabinet and a receptacle (not shown) provided for empty cans.

The electrical circuits for the vending portion of the mechanism are shown in Fig. 5. As illustrated in Fig. 5, both empty switches 57 and 58 are closed because both chutes have at least one can therein. Similarly, empty light switch 61 is open because of the presence of a can in the second chute. Relay 86 is so set that upon deposit of a coin and closing of coin switch 79, vending solenoid 78 will be energized to dispense a single can until the first chute is empty, whereupon empty switch 57 will be opened, and relay 86 will be thrown to the opposite position. Thereafter solenoid 87 will be energized upon the deposit of a coin until all of the cans in the second chute are exhausted, whereupon empty switch 58 will be opened and coin return magnet 88 and relay 86 de-energized, returning subsequently inserted coins to the customer. Empty light switch 61 is simultaneously closed, causing the illumination of empty light 27.

The electrical circuits suitable for performance of the functions described in the preceding paragraph are adequately set forth in said Fig. 5.

Although the present invention has been described in some detail by way of illustration and example, it is understood that certain changes and modifications may be made within the spirit of the invention and scope of the appended claims.

I claim:

1. A chute for a vending machine comprising a pair of substantially parallel, vertical walls spaced apart a distance slightly greater than the height of the articles being dispensed, each of said walls having registering undulating trackways formed of beads protruding inwardly from the opposed wall surfaces, and arranged to engage the ends of the articles being dispensed, said trackways being inclined downwardly and alternating from front to rear, at least one of said walls being formed in a plurality of substantially rectangular sections abutting along horizontal joints, one said section being provided with an ear arranged to overlap a portion of the adjacent section and fastening means passing through said ear and the underlying portion of the adjacent sec-

tion and locking said sections together, said ear comprising a short, angularly shaped member projecting outwardly horizontally and then vertically beyond the horizontal margin of said section, said ear being located remote from said trackway.

2. A chute as defined in claim 1 in which said trackway is formed commencing in the upper forward corner of said section, extending downwardly and rearwardly at a slight declination, having a sharp bend at about the middle of the back thereof and extending forwardly and rearwardly at a slight declination to the lower forward corner thereof.

3. A chute as defined in claim 2 in which the beads on said section are shaped with one bead curved at the upper front corner, then extending straight and inclined downwardly, then at an acute angle at the back, then extending straight and inclined downwardly and then curved at the lower front corner and the other bead extends straight and inclined downwardly from adjacent the forward upper

corner, curved at the middle of the rear and then straight and inclined downwardly to the lower forward corner and in which the radius of curvature of the curved portions is slightly greater than the diameter of the articles being dispensed in the zone of contact of said article with said beads.

4. A chute as defined in claim 1 in which said fastening means comprises a bolt and in which is further provided a plurality of sleeves interposed between parallel walls, said sleeves spacing opposed walls apart the required distance, one of said sleeves and said bolt being positioned remote from said trackway.
